MINING MACHINE WITH RADIALLY ADJUSTABLE BORING ARM

William W. Sloane, deceased, late of Chicago, Ill., by Alice B. Sloane, executrix, Chicago, Ill., assignor to Goodman Manufacturing Company, Chicago, Ill., a corporation of Illinois

Original application December 17, 1952, Serial No. 326,399, now Patent No. 2,730,345, dated January 10, 1956. Divided and this application November 3, 1955, Serial No. 544,678

1 Claim. (Cl. 262—26)

This invention relates to improvements in mining machines adapted to remove coal or similar material from the face of the mine, and more particularly to mining machines of the type having one or more laterally spaced, radial boring arms with cutting devices thereon adapted to cut bores in advance of the machine. The present invention is especially designed as an improvement over the form of mining machine disclosed in the application of Franke Cartlidge and Frank A. Lindgren, Serial Number 255,058, filed November 6, 1951, now Patent No. 2,734,731, wherein the cutter bit supports on the outer ends of the boring arms are telescopically mounted for endwise extension by power means operating from the supporting frame of the rotatable boring member and effective through the drive shaft for said rotatable boring element to adjust the extension of the radial arms while the boring element is in operation.

The principal object of the present invention is to provide an improved form of adjusting mechanism for both extension and retraction of the arms radially of the boring element while the latter is in operation.

Other objects and advantages of the present invention will appear from time to time as the following description proceeds.

The present application is a division of copending application Serial No. 326,399, now Patent No. 2,730,345, and relates more particularly to a variant form of gearing originally shown and described in said parent application.

The invention may best be understood by reference to the accompanying drawings, in which:

Figure 1 is a fragmentary sectional view taken generally along the vertical plane passing through the axis of rotation of a boring element constructed in accordance with the invention and illustrating the environment of the specific, but variant, form of gearing forming the subject matter of the present application;

Figure 2 is a front end view of the boring element shown in Figure 1;

Figure 3 is a detailed section taken on line 3—3 of Figure 1.

Referring now to details of the embodiment of the invention shown in Figures 1 to 3, these three figures illustrate the general form and arrangement of a boring head assembly for which the gearing of the present application is especially designed. In said assembly, a mining machine support or frame is indicated generally at 10 at the front end of which is mounted a boring element indicated generally at 11 adapted to be rotated by power on a generally horizontal axis in advance of the mining machine. In practice, machines of the kind to which the invention relates frequently have two or more similar boring elements rotating on parallel axes so as to cut contiguous bores. Since the present invention is directed more particularly to features of a single boring element, only one such boring element need be shown or described herein.

2

The boring element 11, shown in Figure 1, consists of a radially elongated, hollow supporting frame 12 having an integral hub 13 rotatable in suitable bearings 14 in a gear housing 15 secured to the front end of the main support 10. The cutter arm support 12 is generally hollow and has a pair of radially extending cutter arms 16, 16 mounted for endwise telescopic movement relative thereto. Each cutter arm has a cutter bit support 17 on its outer end, extending at a right angle forwardly therefrom, and having a plurality of detachable cutter bits 18, 18 at its inner, outer and forward end portions.

The boring element 11 may also be provided with a tapered drill-like member projecting forwardly concentric with the hub 13.

15 The inner ends of the radially extending cutter arms 16, 16 are telescopically adjustable in the hollow frame 12 along two parallel guideways 20, 20 formed closely adjacent each other on opposite sides of the axis of rotation of the boring element (see Figure 3). These guideways have wear plates 21 and 22 along the side and front inner faces thereof, engaged by bolts 23, 23 in the hollow frame for adjusting said wear plates relative to the cutter arms when necessary. Each of the guideways 20 has a vertically extending slot 25 opening rearwardly 25 along its inner face through which extend a bracket 26 fixed to the rear face of the respective telescoping arm 16. Each of the brackets 26 has an enlarged end portion 27 in which is threaded a screw shaft 28.

As will be seen from Figure 1, each screw shaft 28 has 30 its outer end journaled in a bearing support 29 carried on the inner face of the hollow frame 12 adjacent the aperture 30 through which its respective cutter arm 16 projects. The inner end of each screw shaft 28 is journaled in a pair of bearing supports 31, 32 projecting 35 inwardly and fixed to the end of the side face of the hollow frame 12. The two screw shafts 28, 28 rotate on parallel, laterally spaced axes, but are disposed in endwise offset relation to each other toward opposite ends of the hollow frame.

40 The hub 13 of the boring element has an adjusting shaft 35 extending axially therethrough and journaled on longitudinally spaced bearings 36 and 37 therein. The outer end of the adjusting shaft 35 may also have a reduced end portion 38 journaled in a cross web 39 of the 45 hollow frame 12, which cross web also forms a part of the guideways 20 for the cutter arms 16. A worm 40 is fixed on the outer end of the shaft 35 in engagement with worm wheels 41, 41 fixed on the two screw shafts 28, 28 between their respective bearing supports 31 and 32.

50 The dual sets of worm gearing and screw shafts are arranged to cause simultaneous telescopic extension or retraction of the cutter arms 16, 16 in the hollow frame 12 when the adjusting shaft 35 is rotated in one direction or the other.

55 The hub 13 of the boring element may be driven through any suitable power-driven gearing, in the form shown in Figure 1 a gear 45 being keyed on the rear end of the hub, and driven by a gear 46 on shaft 47, from any suitable power source on the supporting frame 10.

60 Referring now to the means for operatively connecting the hub 13 with the adjusting shaft 35 so as to rotate the latter in one direction or the other, there is provided a planetary gear mechanism generally indicated at 50, having one element operatively connected with the hub 65 13 of said boring element, a second element operatively connected with the adjusting shaft 35, and a third element arranged for positive rotation by power in one direction or the other under the control of the operator.

70 In the planetary gear mechanism shown in Figure 1, a rotatable member 75 of the planetary system is keyed on the adjusting shaft 35. A planetary gear 76 is car-

ried by the member 75 and is meshed on its periphery with a gear member 77 loosely mounted on the adjusting shaft 35. Gear member 77 has a larger spur gear 77a integral therewith. Planetary gear 76 is also meshed on its outer periphery with an internal gear 78 carried by a gear member 79, also loosely mounted on the adjusting shaft. The last-named gear member 79 has geared connection to the boring element hub 13 through gears 80 and 81 keyed on a shaft 82 fixed on the casing 15, and the gear 45 keyed on the inner end of the hub 13. Rotation of the gear member 77 is effected by a reversing motor (not shown) under control of the operator in any conventional manner, and connected through a shaft 60 having a pinion 61 thereon meshed with external gear teeth 72b formed about a gear 77a which is integral with gear member 77.

The gearing just described is such as to cause rotation of the adjusting shaft 35 in the same direction and at the same speed as the hub 13 when gears 77 and 77a are held stationary by the control shaft 60 and pinion 61. Rotation of the gear 77 by said control shaft in either direction will cause a corresponding rotation of the adjusting shaft 35 with respect to the hub 13.

Although there has been shown and described a certain embodiment of the invention, it will be understood that the invention is not to be limited to the exact construction shown and described, but that various changes and modifications may be made without departing from the spirit and scope of the invention as defined in the appended claim.

What is claimed is:

In a mining machine having a frame and a power-driven boring element rotatably mounted thereon, including a hub and at least one cutter carrying arm adjustable radially of said hub, means for adjusting the position of the arm relative to said hub, including an adjusting shaft extending concentrically through and axially of said hub and operably connected with the arm at the front end thereof to move the latter in response to rotation of said adjusting shaft relative to the hub, the improvement comprising a rotatable member on said shaft, a planetary gear carried by said rotatable member and meshed on its inner periphery with a control gear loosely mounted on said adjusting shaft, and on its outer periphery with an internal gear of a gear member also loosely mounted on said adjusting shaft, said gear member having an external gear having geared connection with the boring element through gears rotatably mounted on the frame, and means for rotating said control gear reversely about the axis of said hub and adjusting shaft, including a control adjusting shaft disposed in an axis parallel with the axis of said hub and adjusting shaft, and having geared connection with said control gear.
